HENRI CONRAD BLANC-GARIN, OF LEVALLOIS-PERRET, FRANCE.

CHANGE-SPEED GEAR.

1,405,391.

Specification of Letters Patent.

Patented Feb. 7, 1922.

Application filed March 7, 1919. Serial No. 281,194.

(GRANTED UNDER THE PROVISIONS OF THE ACT OF MARCH 3, 1921, 41 STAT. L., 1313.)

To all whom it may concern:

Be it known that I, HENRI CONRAD BLANC-GARIN, of 52 Rue Danton, Levallois-Perret, Seine, France, have invented a Change-Speed Gear, (for which I have filed application in France, Feb. 20, 1918, Patent No. 516,360,) of which the following is a full, clear, and exact description.

The present invention relates to a change speed gearing for automobile mechanism in general, but also applicable in all cases where it is a question of reducing at will the speed of a driving shaft, obtaining reduced speed backwards and finally giving the driven shaft a speed equal to that of the driving shaft.

This change-speed gear is characterized by the special combination of a reversing group of epicyclic reducing gear wheels mounted on the driving shaft with an epicyclic rectifying group mounted on the driven shaft, the epicyclic pinions being respectively mounted on the disc fixed to the shaft of the group.

The reducing group reverses the motion of the driving shaft, while the other group restores the direction of working.

The apparatus is worked by fixing or locking one or other of the pinions of one of the two groups by means of any suitable device, such as a brake band for example, in such a way as to transmit the motion to the driven shaft.

In practice it results from this system that the excessive speed of certain gears, which is common in the systems usually employed, whether in use or unclutched, is eliminated, and also that the noise and the premature wear resulting from this excessive speed are also eliminated.

This advantage is particularly important when it is a question of obtaining speeds in the neighbourhood of the initial speed.

Furthermore the system to which this invention relates offers the following practical advantages:—

(1) The possibility of obtaining a new range of speeds from the gears that have already been concerned in obtaining other speeds.

(2) The possibility of obtaining for the

driven shaft a speed equal to that of the driving shaft without the addition of a flexible or progressive clutch.

(3) The possibility of obtaining instantaneously a reduction or an increase of the speed in operation.

(4) The possibility of instantaneously obtaining reversal at reduced speed from any one of the speeds in operation.

(5) The possibility of obtaining different speeds shown in the accompanying drawing wherein:—

Figures 1 and 1^A laid side by side, show a longitudinal sectional elevation of a constructional form of this invention, on the line X—X in Figure 3.

Figures 2 and 2^A similarly show a longitudinal sectional elevation of the same apparatus, on the line Y—Y in Figure 3.

Figure 3 is a cross section of the apparatus, on the line Z—Z in Figure 1^A.

Figure 4 is a cross section of the apparatus, on the line W—W in Figure 1.

Figures 5 and 5^A, laid side by side, show cross sections through the various pinions of the reducing reversing group, corresponding with Figures 1 to 4 of the drawing.

Figures 6 and 6^A similarly show cross sections through the various pinions in agreement with the rectifying group, corresponding to Figures 1 to 4 of the drawing.

Figure 7 shows diagrammatically the gears in operation for the third speed (permitting of direct drive).

Figure 8 shows the gears in operation for the second speed.

Figure 9 shows the gears in operation for the first speed.

Figure 10 shows the gears in operation for working backwards.

Figure 11 is a diagrammatic view showing the means of obtaining very wide differences of speed in change-speed gear of this type.

Figure 12 is a detail view—partly in section—showing means for operating pawl or clutch devices.

Figure 13 is a detail sectional view showing means for the mounting of intermediate pinions.

The apparatus which forms the subject-matter of the present invention, and which

is shown in the accompanying drawing, comprises a driving shaft A and a driven shaft B.

On the same side as the driving shaft A 5 is located the reducing reversing group A¹, (Fig. 1^A.)

On the same side as the driven shaft B there is the rectifying group B¹, (Fig. 1.)

A disc A² forming part of the reducing 10 group A¹ is fixed to the driving shaft A.

Another disc B² forming part of the rectifying group B¹ is fixed to the driven shaft B.

The disc A² is provided with three pairs 15 of epicyclic pinions a, a¹, a², a³, a⁴ and a⁵ (Figs. 5, 5^A), the members of each pair being virtually integral with each other.

The disc B² is provided with three pairs 20 of epicyclic pinions b, b¹, b², b³, b⁴ and b⁵ (Figs. 6, 6^A), the members of each pair being virtually integral with each other.

The pair of epicyclic pinions a, a¹ of the disc A² is connected by means of the pinion a with a pinion c virtually integral with a 25 drum c¹ for forward travel, provided with a ratchet d, and by means of the pinion a¹ with a pinion e, virtually integral with a sleeve e¹, connecting the reducing reversing group A¹ with the rectifying group B¹.

30 The pair of epicyclic pinions a², a³ is connected by means of the pinion a² with a pinion f virtually integral with the drum f¹ for backward working, provided with the brake band f², and by means of the pinion a³ 35 with a pinion e, virtually integral with the sleeve e¹, forming part of the reducing group A¹.

The pair of epicyclic pinions a⁴, a⁵ is 40 connected by means of the pinion a⁴ with a pinion g virtually integral with a drum g¹ for forward working, provided with a brake band h.

Each pair of epicyclic pinions is therefore connected by means of one of its pinions 45 with the pinion e, the said epicyclic pinions being a¹, a³, and a⁵.

The pair of epicyclic pinions b, b¹ of the disc B² is connected by means of the pinion b with the pinion e² and by means of the pinion b¹ with a pinion k virtually integral with a drum k¹ provided with a brake band l.

50 The pair of epicyclic pinions b², b³ is connected by means of the pinion b² with the pinion e² coming from the reducing group 55 and by means of the pinion b³ with a pinion m virtually integral with a drum m¹ provided with a brake band n.

The pair of epicyclic pinions b⁴, b⁵ is 60 connected by means of the pinion b⁴ with the pinion e² of the reducing group and by means of the pinion b⁵ with the pinion i, virtually integral with the drum i¹ provided with the brake band j.

65 Each pair of pinions is therefore connected by means of one of its pinions with

the pinion e², the said epicyclic pinions being b, b², b⁴.

By way of example the numbers of teeth in the various pinions may be as follows:—

a = 28 teeth	b ⁴ = 30 teeth	70
a ¹ = 30 "	b ⁵ = 27 "	
a ² = 31 "	c = 17 "	
a ³ = 30 "	e = 15 "	
a ⁴ = 27 "	e ² = 15 "	75
a ⁵ = 30 "	f = 14 "	
b = 30 "	g = 18 "	
b ¹ = 25 "	i = 18 "	
b ² = 30 "	k = 20 "	
b ³ = 21 "	m = 24 "	

The numbers of teeth in the various pinions engaging therewith may be as follows:—

Reducing reversing group.	Rectifying group.	
a = 28 } = 45 teeth	b = 30 } = 45 teeth	85
c = 17 } "	e ² = 15 } "	
a ¹ = 30 } = 45 teeth	b ¹ = 25 } = 45 teeth	
e = 15 } "	k = 20 } = 45 teeth	
a ² = 31 } = 45 teeth	b ² = 30 } = 45 teeth	90
f = 14 } "	e ² = 15 } "	
a ³ = 30 } = 45 teeth	b ³ = 21 } = 45 teeth	
e = 15 } "	m = 24 } = 45 teeth	
a ⁴ = 27 } = 45 teeth	b ⁴ = 30 } = 45 teeth	
g = 18 } "	e ² = 15 } = 45 teeth	
a ⁵ = 30 } = 45 teeth	b ⁵ = 27 } = 45 teeth	95
e = 15 } "	i = 18 } "	

The various reductions are obtained in the following manner:—

On referring to Figure 9 of the accompanying drawing it will be seen, for example, that at the first speed, that is to say the lowest speed, if we make the pinion g stationary in the reducing group A¹ we obtain, about this pinion, the rotation of the epicyclic pinion a⁴ driven by the driving disc 105 A² and the rotation through an equal angle of the epicyclic pinion a⁵, which is virtually integral with the epicyclic pinion a⁴, which has the result of bringing about the rotation, in the opposite direction, of the pinion e. 110

This speed of the pinion e, reduced and reversed from the driving shaft A, is taken up by the rectifier B¹ by means of the epicyclic pinion b², mounted on the disc B² of the rectifier and gearing with the reversing pinion e². 115

The epicyclic pinion b² is virtually integral with the pinion b³ to which it communicates the said reversed velocity, still further reduced by the ratio of the gears e² and b²: the pinion b³ which is in gear with the pinion m, communicates this velocity to the latter.

By rendering the pinion m stationary, we obtain, about the latter, the rotation of the epicyclic pinion b³, and consequently that of the disc B² of the driven shaft B, under the action of the pinion e² acting on the epicyclic pinion b², which is virtually integral with the pinion b³. 125

At the second speed, Figure 8, the speed of the pinion e , reduced and reversed from the driving shaft A, is taken up by the rectifier by means of the epicyclic pinion b mounted on the disc B^2 and gearing with the reversing pinion e^2 .

The epicyclic pinion b is virtually integral with the pinion b^1 , to which it communicates the said reversed velocity still further reduced by the ratio of the gears e^2 and b ; the pinion b^1 , in gear with the pinion k , communicates this speed to the latter.

By fixing the pinion k , we obtain, about the latter, the rotation of the epicyclic pinion b^1 , and consequently, that of the disc B^2 of the driven shaft, under the action of the pinion e^2 , acting on the epicyclic pinion b , virtually integral with the pinion b^1 .

For the third speed, as indicated by Figure 7, the speed of the pinion e , reduced and reversed from the driving shaft A, is taken up by the rectifier by means of the epicyclic pinion b^4 , mounted on the disc B^2 and gearing with the reversing pinion e^2 .

The epicyclic pinion b^4 is virtually integral with the pinion b^5 , to which it communicates the said reversed velocity, reduced still further by the ratio of the gears e^2 and b^4 ; the pinion b^5 , in gear with the pinion i , communicates this speed to the latter.

By locking the pinion i we obtain, about the latter, the rotation of the epicyclic pinion b^5 , and consequently that of the disc B^2 of the driven shaft under the action of the pinion e^2 acting on the epicyclic pinion b^4 , which is virtually integral with the pinion b^5 .

For reversed working, as shown in Figure 10 of the drawing, the locking, in the reducing group A^1 , of the pinion f , brings about the rotation of the pinion a^2 under the action of the driving disc A^2 , which this time has the result of driving, through the medium of the pinion a^3 at a greatly reduced speed, the pinion e , in the same direction as the driving shaft A, and in this way of reversing the working of the disc B^2 which is virtually integral with the driven shaft B, whatever gears may be in operation in the rectifying group.

For the reduction of speed while running forwards, it will be seen, in Figure 11, that by locking the ratchet drum c^1 (see Figures 5, 5^a) which is virtually integral with the pinion c in gear with the pinion a , the ratios of the gears a and c substituted for the gears a^4 and g have the result of reducing the speeds that have been indicated above, which makes a new range of speeds available in the rectifier.

For direct driving it will be seen, by examining the diagrammatic Figure 7, (third speed), that all the gears in the reducing and reversing group have their diametral

concordance with the gears in the rectifying group; it follows therefore that at this speed the disc B^2 , and consequently the driven shaft, are rotating at a speed equal to that of the disc A^2 , which is virtually integral with the driving shaft. If for example at this moment pawls or clutches o (see Figures 1, 1^a and 3), arranged concentrically on the driving disc A^2 , are liberated by means of a suitable device (see Fig. 12) virtually integral with the gear casing, a locking will be obtained which renders the driving shaft A virtually integral with the driven shaft B. The locking of the drums g^1 and i^1 is then superfluous and the liberation thereof permits the change-speed gear as a whole to rotate at the speed of the driving shaft in its bearings p , which are virtually integral with the gear casing, without the use of any resilient clutch.

In Figure 11 of the drawing a means has been indicated for obtaining very wide differences of speed between the two shafts in change-speed gearing of this system. This difference is in accordance with the formula of Willis and depends upon the number of teeth in each pinion utilized for obtaining the speed in question. Taking for example the first speed A, V Fig. 14, it will be seen that the pinions g and m are fixed since they are fast on the brake drums g^1 and m^1 respectively, and assuming the pinions have the following number of teeth (as set forth above), viz: $a^4=27$ teeth, $a^5=30$ teeth, $b^2=30$ teeth, $b^3=21$ teeth, e and e^2 each 15 teeth, $g=18$ teeth, $m=24$ teeth; now for one turn of the driving shaft A carrying the planetary group a^4 to a^5 :

$$\frac{g \times a^5}{a^4 \times e} = \frac{18 \times 30}{27 \times 15} = \frac{4}{3} = 1.33. \quad 105$$

The absolute angular velocity of the driven pinion e is equal to $1 \times (1-1.33) = 0.33$ or $\frac{1}{3}$ of a revolution in a direction opposite to the direction of A. For the driving pinion e^2 are the following values:

$$\frac{e^2 \times b^3}{b^2 \times m} = \frac{15 \times 21}{30 \times 24} = \frac{7}{16} = 0.4375. \quad 115$$

The angular velocity of the shaft B is equal to

$$-0.33 \left(\frac{0.4375}{0.4375-1} \right) = -0.33 \times (-0.775) = +0.255, \quad 120$$

that is, about $\frac{1}{4}$ revolution in the same direction as A. It will thus be seen that the speed reduction is 1:4 and that the direction of rotation is the same. This means 125 comprises a group of intermediate pinions w , mounted in the manner indicated at Fig. 13 and placed between the reversing sleeve and the rectifying group. In this case the epicyclic pinions may be mounted 130

either loose on the shafts that carry the epicyclic pinions of the rectifier, or else on independent shafts, as indicated in dotted lines. Similarly, any intermediate sleeve 5 carrying pinions charged with the duty of connecting the epicyclic gearings may be mounted in one group or the other on the central shaft.

The forms, details, accessories, materials 10 and dimensions of this apparatus may of course be varied without affecting in any way the principle of the invention. Thus for example each shaft carrying epicyclic pinions may be duplicated or triplicated 15 about the central shaft. The reduction obtained by means of the epicyclic pinions may be divided into two stages by means of a second shaft receiving motion from the first and restoring it thereto after reduction, the transmitting and receiving pinions 20 of the first shaft, being of course independent of one another, and being in case of need each mounted on a shaft of its own.

Claims:

25 1. A change speed gear comprising a driving shaft, a driven shaft arranged in alignment with this driving shaft, a reversing shaft the axis of which coincides with that of the two previous shafts, a pinion loosely 30 mounted on the driving shaft, a gear carried by the reversing shaft, a double epicyclic group of gears mounted on the driving shaft and gearing on the one hand with the said loosely mounted pinion and on the 35 other hand with the gear carried by the reversing shaft, means for locking at will the loosely mounted pinion, a second pinion loosely mounted on the driven shaft, a second gear carried by the reversing shaft, 40 a double epicyclic group of gears carried by the driven shaft and gearing, on the one hand, with the latter loosely mounted pinion and, on the other hand with the latter gear carried by the reversing shaft, and 45 means for locking at will this latter loosely mounted pinion.

2. A change speed gear comprising a driving shaft, a driven shaft arranged in alignment with this driving shaft, a reversing 50 shaft the axis of which coincides with that of the two previous shafts, a pinion loosely mounted on the driving shaft, a gear wheel carried by the reversing shaft, a double epicyclic group of gears carried by the 55 driving shaft and gearing, on the one hand with the loosely mounted pinion, and on

the other hand with the gear wheel carried by the reversing shaft, means for locking at will this loosely mounted pinion, a second pinion loosely mounted on the driven 60 shaft, a second gear wheel carried by the reversing shaft, a double epicyclic group of gears carried by the driven shaft and the pinions of which have respectively the same 65 diameters as those of the double epicyclic group of gears carried by the driving shaft and are in gear, on the one hand with the second loosely mounted pinion, and on the other hand with the second gear wheel carried by the reversing shaft, this second 70 loosely mounted pinion and second gear wheel having respectively the same diameters as the loosely mounted pinion and gear wheel of the reversing shaft with which gear the double epicyclic group of gears 75 mounted on the driving shaft, means for locking this second loosely mounted pinion gearing with one of the pinions of the double epicyclic group of gears carried by the driven shaft, and means for directly connecting the driving shaft and the driven 80 shaft.

3. A change speed gear comprising a driving shaft, a driven shaft arranged in alignment with this driving shaft, a reversing 85 shaft the axis of which coincides with that of the two previous shafts, a pinion loosely mounted on the driving shaft, a gear wheel mounted on the reversing shaft, a double epicyclic group of gears carried by the driving shaft and gearing, on the one hand with the loosely mounted pinion, and on the other hand with the gear wheel mounted on the reversing shaft, means for locking at will this loosely mounted pinion, a second 90 pinion loosely mounted on the driven shaft, a second gear wheel carried by the reversing shaft, a double epicyclic group of gears carried by the driven shaft and gearing, on the one hand with the second 95 loosely mounted pinion, and on the other hand with the second gear wheel carried by the reversing shaft, and means for locking at will this second loosely mounted pinion, the first mentioned loosely mounted 100 pinion having a diameter smaller than the first mentioned gear wheel on the reversing shaft.

The foregoing specification of my change speed gear signed by me this seventh day 110 of February 1919.

HENRI CONRAD BLANC-GARIN.
